UNITED STATES PATENT OFFICE.

FRANK S. BALDWIN AND PHILLIP A. MIGASI, OF ST. LOUIS, MISSOURI.

REIN-HOLDER.

SPECIFICATION forming part of Letters Patent No. 276,655, dated May 1, 1883.

Application filed November 10, 1882. (No model.)

To all whom it may concern:

Be it known that we, FRANK S. BALDWIN and PHILLIP A. MIGASI, residents of St. Louis, Missouri, have jointly made a new and useful Improvement in Safety-Reins and Hitching-Straps, of which the following is a full, clear, and exact description, reference being had to the annexed drawings, making part of this specification, in which—

10 Figure 1 is a side elevation, showing the improvement in position. Only that portion of the carriage-axle and wheel-hub is shown as is immediately connected with the improvement, and portions of the construction are broken away to exhibit the interior mechanism. Fig. 2 is a section taken on the line 2.2 of Fig. 1, a portion of the casing being broken away; Fig. 3, a section taken on the line 3.3 of Fig. 1; Fig. 4, a section similar to 15 that of Fig. 3, the lever being in a different position, and the hub and hub-casing not being shown; and Figs. 5, 6, 7, 8, details.

The same letters of reference denote the same parts.

25 By means of the present improvement the forward movement of a horse harnessed to a vehicle can be controlled and arrested.

A represents the axle of a carriage.

B represents the hub of one of the carriage-wheels.

30 C represents a frame fastened to the axle—that is, the frame consists essentially of a part, c, which rests upon the axle, and two uprights, c' and c'', which extend upward 35 above the part c, and also downward at c' c'' below the axle, similarly to a clip, and by means of the plate c⁴ and nuts c⁵ c⁶ the frame is secured to the axle. The uprights c' c'' are perforated to receive a shaft, D, which passes 40 through the uprights, and at its outer end is furnished with a roller, d, and at its inner end sustains a drum, d'. The roller d is fastened to the shaft D, and rotates with it whichever way the shaft turns; but the drum rotates 45 with the shaft only in one direction, the drum having a ratchet, d², and the shaft having a collar, d³, and pawl d⁴, the pawl engaging in the ratchet d² and serving to connect the shaft and drum when the horse is moving 50 forward.

E represents a cam attached loosely to the

shaft D, and having a lever-arm, e, by means of which the cam can be turned around on the shaft D.

F represents a casing, which is attached to 55 and rotates with the hub B, and preferably by means of the set-screws f f'.

The upright c' is provided with a projection, c⁶, and there is a bearing, c⁷, upon the part c. The cam E works between the projection c⁶ and the bearing c⁷, and as the cam is turned around on the shaft D it causes the shaft to be elevated or lowered, as the case may be, and the roller d to be brought against the rim f' of the casing or against the hub B. 60 This movement is indicated by the dotted and full lines in Fig. 2. The opening c⁸, Fig. 5, in the upright c' is suitably elongated to provide for the movement, as described, of the shaft D. The bearing c⁹ in the upright c² is 65 also suitably rounded to suit the movement of the shaft.

A strap (not shown) leads from the drum d' to the horse's mouth, and a suitable cord (also not shown) leads from the outer end of 70 the lever e to within reach of the occupant of the carriage.

The operation is as follows: When it is desired to check the horse slightly the lever e is moved to cause the roller d to bear slightly 80 against the rim f' or the hub B. The effect is to wind the strap (that leads to the horse's mouth) upon the drum, and to exert a slight friction-tension upon the strap, and to hold the horse to some extent, the roller d slipping after a 85 certain tension is produced; but when it is desired to arrest the horse, as when the occupant leaves the carriage, the lever e is moved to throw the roller d hard against the rim f' or hub B. The strap is then wound more and 90 more upon the drum as the carriage is drawn along, and in consequence the strap draws more and more upon the horse, and the effect is to hold the horse as effectually as if tied to a hitching-post; but in all cases, after a certain degree of tension, the roller d slips upon the rim f', and the device in consequence, while serving to check the horse, is prevented from injuring him, and in turn is not liable to breakage, both of which difficulties are apt to 95 occur when the motion of the wheel is transmitted through toothed gearing to the rein.

holder drum. Should the horse back, the drum, by reason of the pawl-and-ratchet connection above described, does not rotate, and the strap in consequence does not draw upon the horse.

The casing F also serves to protect the roller *d* from the dirt.

We claim—

For the purpose described, a shaft revolving in bearings upon a vehicle-axle and receiving

its motion from the wheel through friction-rolls, the tension of said friction-rolls being adjusted by means of a cam-lever, substantially as shown.

FRANK S. BALDWIN.
PHILLIP A. MIGASI.
